UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

DECONCENTRATOR.

Application filed May 4, 1925. Serial No. 27,850.

My invention has to do with the art of boiler operation. Specifically it is concerned with a method and apparatus for continuously ridding boilers and other evaporators 5 of various kinds of the foreign substances which enter with the feed water or other liquid and remain in the pressure vessel while the liquid, being evaporated, goes off as vapor.

10 The herein presented solution of the problem is extremely simple and will be readily understood on reference to the accompanying drawings and the following detailed description.

15 In said drawings, Fig. 1 illustrates an ordinary water tube boiler equipped with deconcentrating apparatus embodying my invention; Fig. 2 is an enlarged vertical section of the upper drum and the centrifugal 20 unit which plays an important part in this system; and Fig. 3 is a horizontal section on the line 3—3 of Fig. 2.

The typical boiler of Fig. 1 comprises a setting or fire chamber 2, a bottom drum 3, 25 one or several top drums 4, and a large number of tubes 5 connecting the drums. The feed water is supplied to the boiler through either the bottom drum or the top drum, as usual. The steam or other vapor leaves the 30 boiler through the outlet nozzle 6.

A boiler water circulating pipe or loop 7 is arranged outside the setting or wall 2, with its upper end connected with the lower part of the upper drum and with its lower 35 end connected to the bottom drum. This pipe is constantly open and is occupied by a solid column of boiler water, so much heavier than the columns of mixed water and steam in the tubes 5 that a rapid downward flow is constantly maintained in the 40 pipe 7.

The upper end of the pipe 7 is joined to the end of the drum 4 by a coupling 8 which on the inside of the drum turns upward to 45 form the elbow 9. This elbow, as shown, opens some little distance below the low water line 10 of the boiler. The top of the elbow preferably bears a circular collar 11. The part 9 is enclosed by a casing arranged 50 directly within the fire-protected end of the boiler drum, that is, in the part which extends beyond the wall 2. The casing, as best shown in Figs. 2 and 3, comprises the vertical wall 12 and the top plate 12', having 55 their edges attached to the walls of the

drum. The top plate is positioned above the level of the collar 11 and contains a hole 13 directly above the collar and central opening 9' of the elbow 9. On the plate 12' is a tangential tuyère ring *a* which comprises the top or end disk 14 and a circumferential series of operatively overlapping tangential tuyère blades 15, the latter having their lower ends fastened to the part 12' at the margin of the hole 13. The internal 60 diameter of the tuyère ring *a* is greater than that of the opening 9'. A suitably valved blow-off pipe 16 leads from the bottom of the cavity *b* within the casing 12, 12'.

As previously explained, when evaporation is going on, there is a constant flow of water downward through the pipe 7 (whether or not the latter is insulated) and to reach the pipe 7 the water from the upper drum must pass through the tangential tuyères *a'* of the tuyère ring *a*. The aggregate area of these tuyères is considerably greater than the area of the circulating pipe 7 and the flow through the tuyères is rapid. Due to its manner of entrance the water 70 takes on a rapid whirling motion within the tuyère ring *a* and within the circumferential space *c* (between the parts 11 and 12') above the opening 9'. This whirling or swirling of the water results in centrifugally 75 separating the heavier substances, and, while the cleared water passes freely downward through the conduits 9 and 7, the heavier substances are thus removed from the region of the outlet 9' and are collected in the cavity *b*. The occasional blowing off of the 80 contents of that cavity serves to keep the boiler substantially clean.

As will now be apparent, this invention 85 performs the combined functions of a skimmer and a deconcentrator, with the advantage that practically no boiler water is wasted. Various practical modifications will suggest themselves to those skilled in the art and it is to be understood that the invention is not limited to the exemplary structure herein shown.

Having thus described my invention I claim as new and desire to secure by Letters Patent:

1. A steam boiler having a sediment collecting pocket in a fire protected position within its upper part but below the boiler water level, in combination with a whirl-promoting tuyère also below said water level 105 110

and forming the entrance to said collecting pocket, an outlet centrally beneath said tuyère to receive the clear water therefrom, a pipe leading from said outlet back into the lower part of the boiler, and means for blowing the sediment from the lower part of said pocket.

2. A steam boiler drum and its setting, in combination with a sediment separator having a sediment pocket and positioned within the boiler drum directly beneath the

low water level therein, said separator having clear water and sediment outlets both below said level and both communicating with said pocket, a blow-off connection 15 joined to the sediment outlet, and a recirculating connection leading from the clear water outlet of the separator to a lower part of the boiler.

In testimony whereof I have hereunto set 20 my hand this 30th day of April A. D. 1925.

CHARLES GILBERT HAWLEY.
